UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

FOLDER.

Application filed August 8, 1922, Serial No. 580,437. Renewed June 1, 1926.

The principal objects of this invention are to provide for operating a folder at a high rate of speed; to provide improvements in the nipping rolls of the folder to prevent 5 the failure of these rolls to pull the paper snugly over the former when running at high speed; to provide for so arranging the folding roller supports that they will move directly away from the folding cylinder when 10 a choke of paper occurs, thus relieving the choked condition while it is occurring and leaving the paper in such position that when the press is eventually stopped the paper can be taken out by the use of the hands only 15 without the employment of tools which are likely to injure the rolls or other parts of the press; and to provide all these devices in a single mechanism arranged to cooperate with each other to deliver and fold sheets at a 20 very high rate of speed.

Reference is to be had to the accompanying drawings, in which

Fig. 1 is a side view of a newspaper folding machine constructed according to this 25 invention;

Fig. 2 is a sectional view through the delivery mechanism on enlarged scale;

Fig. 3 is a diagrammatic view showing the path of the paper;

Fig. 4 is a diagrammatic view showing the drive for the nipping rolls;

Fig. 5 is a side view showing the spring pressed brackets for the nipping rolls;

Fig. 6 is an elevation of the fan shaft and 35 associated parts looking in the direction of the arrow 6 in Fig. 2;

Fig. 7 is a view of folding cylinder and folding rolls in normal position;

Figs. 8 and 9 are similar fragmentary views 40 showing how folding rolls can be adjusted so that path of paper can be changed to the right or left of center line;

Fig. 10 is a plan view of folding rolls;

Fig. 11 is a sectional view on the line 11— 45 11 of Fig. 10;

Fig. 12 is a view of one end of said arrangement looking in the direction of the arrow 12 in Fig. 10; and

Fig. 13 is a sectional view through the 50 shearing pin on the line 13—13 of Fig. 12.

I find that when newspaper folding devices are run at great speed an ordinary set of nipping rolls does not pull the paper snugly over the former folder. If they are set 55 tight enough on the paper to accomplish this

object they bring too great a strain on one of the paper streams and it cracks or breaks through at that point. To overcome this difficulty I provide for dividing up this strain between two or more sets of nipping rolls. 60

Ordinarily the folding rolls which cooperate with the cutting cylinder are arranged so that when extra strain is put upon them they will move apart oppositely and horizontally or in a general tangential direction. 65

Now when a choke of paper occurs it usually accumulates between the folding cylinder and the folding roll nearest the cutting cylinder, and some of it between the two folding rolls which are capable of being pushed apart as 70

stated. The direction of motion of these folding rolls as stated above, is such as to make it hard to dig out the compressed paper. Chisels or hammers often have to be used, resulting in damage to the parts and waste of 75

time. I have provided for obviating these difficulties by so arranging the rollers that they move substantially radially away from the cylinder, thus relieving the choked condition as it occurs, and not permitting the 80 paper to accumulate here in a hard mass. Therefore it is easy to take it out by the use of the hands only and without wasting any great amount of time. This operates by

directly providing, by the action of the heavy 85 pressure of packing, more space between the rollers and cylinder as each new sheet is pushed into the gap. I also provide a cut off pin that is fractured when the pressure

gets too heavy, thus creating a wide space 90 suddenly and avoiding the keeping of the packed paper under pressure. This pin can then be pulled out and another inserted and the press started up saving a great deal of time and trouble and avoiding damage. 95

The delivery fan is provided with stops adjustable simultaneously for changing the effective depth of all pockets of the fan, thus reducing the time required for setting up the device properly. With this is connected an 100 oscillating counting device that pushes more than one product or sheet up on the pile each time it operates, so that the gap can be readily distinguished. This is provided to avoid the difficulty which so frequently occurs, due to 105 the fact that only one sheet is advanced at the end of a pile, and consequently it has been difficult to determine where the stack terminates.

I have shown the invention as applied to 110

a folding mechanism having the ordinary features well known in this art and the improvements above mentioned added to them. This machine is shown as comprising a former 10 operating with the usual forming or leading-in rolls 11, and the usual pair of nipping rolls 12 which I call the primary nipping rolls. On account of the difficulties above mentioned and for the purpose of dividing up the strain I do not depend entirely upon these two nipping rolls. But I provide in addition a secondary pair of nipping rolls 13 spaced from the first pair and operating in the same way. With this device it is not necessary to adjust the rolls 12 tight enough to cause them to pull the paper snugly over the former folder 10 at all times, but they can be adjusted more loosely because they are assisted by the second rolls 13 which also are adjusted loosely. The work is divided between the plurality of sets and the strain at each point is divided and lessened. This practically eliminates the cracking or breaking of the paper at the nipping rolls.

25 I have shown one of the upper pair of nipping rolls 12 mounted on a stationary shaft and the other on a shaft mounted on pivoted brackets 14. These brackets are pressed by adjustable springs 15 toward the other roll of the couple and this adjustment may be made by a worm and screw 16 or in any other desired way. One of the rolls 13 of the other pair is also mounted on a stationary shaft on the frame of the machine and the other on a bracket 17 which is pivoted and adjusted by springs 15 and screws 16 as in the other case.

40 The web W is led as usual from the nipping rolls to the folding cylinder 18 and cutting and collecting cylinder 19 which cut it up into sheets and fold it in the usual way and tuck it between the folding rolls 20.

The folding rolls 20 are mounted on shafts 21 as usual rotated and geared together by gears 20*. One of these shafts has bearings 45 at its ends mounted on brackets 22 and these brackets are pivoted on a shaft 23 which is carried in a pair of supports 24 at the two ends of the machine. These supports are provided with slots 25 arranged concentric 50 with the folding cylinder. The frame of the machine is provided with bolts 26 for securing the adjustment of these supports in any desired position. Extending downwardly from the support 24 there is an arm 40 which 55 is provided with an adjusting screw 41 engaging the frame for moving each of the supports 24 back and forth.

60 On the supports 24 there is a breaking pin 27 which constitutes a pivot shaft for brackets 28 on which the other roll 20 of the pair has its bearings. These brackets extend beyond this roll and are provided with studs 29 which carry rods 30 extending downwardly therefrom at an angle and provided with 65 springs 31 and adjusting nuts and collars 32.

On the supports 24 there is a shaft 33 extending across the machine having two worms 34. One of these worms at one end of the machine is fixed to the shaft and the one at the other end of the machine is loose on the shaft 70 but fixed to a loose hub 35 on the shaft and provided with a hand wheel 36 for adjusting it. Also keyed or otherwise fixed to the shaft 33 is another similar hand wheel 37 for adjusting the other worm. These two worms 75 can be turned together by turning the two hand wheels or either one can be adjusted alone by its own hand wheel. Each of these worms meshes with a worm wheel 38 on one of the rods 30 for adjusting the pressure of 80 the springs 31.

In this way one of the two rolls 20 can have the spring pressure with which it is provided adjusted to regulate the difficulty of forcing it away from the folding cylinder 85 18. It will be noted that the brackets 22 and 28 cross each other so if the breaking pin breaks they both can move away, one about the pivot 23 and the other about the pivot 27 on the opposite side in directions substantially radial with respect to the folding cylinder. One roll is always free to move away in that direction, this movement being resisted only by the springs 31 which are provided for that purpose, and which hold the 90 two rolls in contact unless some choke of paper occurs to overcome the resistance of these springs and force one away. This relieves the choked condition as it occurs and prevents the packing of the paper between the rolls and the folding cylinder in a hard mass, and also permits the paper to be taken out without the use of tools. As the paper is packed in between these rolls they yield more 100 and more to provide a space for it.

105 I have described the arrangement by which one of the rollers is pressed on by the springs 31 to hold it against the other. In addition to this I have shown in the last two figures the cut off or fracture pin 27 mounted at the pivot 110 point of the bracket 28 in position to enter a hole 43 provided in a sleeve passing through holes in the brackets 22 and 28 and in the support 24. The brackets 22 are stationary ordinarily. Now when the movable roller is 115 pressed too hard away from the other this pin 27 will break and all the resistance will be relieved at once, thus creating suddenly a sufficient space for the wad of paper. This paper therefore is no longer kept under pressure. The bracket 22 comes down against the support 24. When this occurs the press is stopped, the paper pulled out, the pin also pulled out, and another pin 27 inserted. Then 120 the press can be started and will operate as if nothing had happened.

125 From the folding rolls the folded product comes down as usual against a set of stop arms 45 mounted on brackets 46 which are fixed in adjusted position and remain sta- 130

tionary during the operation of the machine as is usual. Interspersed among these arms are a series of fan blades 47 mounted on a shaft 48 which rotates them. These blades 5 ordinarily are provided with pockets between them which are of constant depth, but I have arranged in addition to these pockets a star-wheel 49 on the shaft 48 provided with slots 50 concentric with the shaft. Through these 10 slots pass bolts 51 mounted in fixed position with respect to the shaft, so that the star wheel can be adjusted through an angle. The star wheel is provided with a series of radial stops 52, each one extending into one of the 15 pockets of the fan and constituting the bottom of that pocket. By the adjustment of the star wheel the effective depth of the pockets is also adjusted and they are all adjusted simultaneously and equally. It will be understood, 20 of course, that these stops 52 do not need to project into the pockets, but two sets of them are shown located between some of the fans so as to have the effect above described.

This fan lays the folded sheets on a conveyor belt 54 as usual. Being laid at regular intervals and the blades moving continuously, each folded product is laid at a definite distance behind the one previously deposited in the usual way. As deposited the folded products come up against fixed stops 55.

It has been customary heretofore to provide means for pushing one sheet or folded product up into registration with the next one whenever the desired number have been 25 laid on the belt. This constitutes an ordinary method of counting out fifty or one hundred or any other number of sheets. I find that it is not easy to distinguish the point of division between two bundles of products in 30 this way, and for that reason I provide the shaft 60 by which the conveyor belt 54 is operated with a cam 61 having a notch 62 therein. This cam rotates like the shaft 60 once for each fifty or any other desired number of 35 printed products deposited. It is arranged to operate on the roll 63 on an arm 64 on a shaft 65. This shaft carries another arm 66 which is pulled over by a spring 66^a to hold the roller 63 in contact all the time with the 40 cam 61. The arm 66 is connected by an adjustable link 67 with a second adjustable link 68 pivoted on a stud 69. To the end of this link 68 is pivoted a stopping finger 70 held up by a spring 71. Each time the cam 61 45 rotates a full revolution the roller 63 enters the notch 62 and allows the link 67 to move forward toward the left in Fig. 2. This swings the lever 68 and the finger 70 forward also a distance sufficient to pile up two or more 50 of the printed products with their butt ends in alignment with each other. In this way the gap between these and the next deposited sheets or products will be sufficient to avoid all danger of over-looking the same. This is 55 important because inexperienced or young

operators are employed ordinarily to take these bundles off and place them in piles ready for distribution or other operations.

All these improvements are designed to facilitate the speeding up of a folding device 70 of the character indicated in the drawings. They are provided to solve certain problems which arise when the speed of the folder increases materially beyond the highest rates heretofore considered practical and they co-operate to that end. I do not claim herein 75 the details of the delivery fan and the nipping rolls, as they are the subject matter of my co-pending divisional applications, Serial Nos. 3,509 and 3,510, filed Jan. 19, 1925.

Although I have illustrated and described only a single form of the invention and shown it as applied to one type of folder I am aware of the fact that modifications can be made therein by any person skilled in the art 85 without departing from the scope of the invention as expressed in the claims. Therefore, I do not wish to be limited in these respects, but what I do claim is:

1. In a folding machine, the combination 90 with a rotary folder comprising a folding and a cutting cylinder for receiving the web, of a primary and a secondary pair of nipping rolls located at a distance apart for nipping the web and feeding it to the folder, and a 95 pair of folding rolls for receiving the folded product from the folder, one of the folding rolls being mounted to yield in case of excessive strain in a substantially radial direction with respect to the folding cylinder. 100

2. The combination with a folder comprising a folding cylinder and a cutting cylinder cooperating therewith, of a pair of folding rolls located in position to receive the folded product from said folding cylinder, and 105 means whereby one of said rolls will move automatically away from said cylinder in a substantially radial direction in case of the choking of the paper between them and the folding cylinder. 110

3. The combination with a folding cylinder and a pair of folding rolls for receiving the folded product therefrom, of means for supporting said folding rolls in a position to permit one of them to yield in case of excessive strain in a direction substantially radial with respect to said cylinder. 115

4. In a folding machine, the combination 120 with a pair of folding rolls for receiving the folded product, of pivoted brackets on which said rolls are journalled, the pivots of the brackets for each roll being located on the side of the other roll opposite the cylinder, whereby said brackets can be swung on their pivots to bring their respective rolls away 125 from the cylinder.

5. In a folding machine, the combination 130 with a folding cylinder and a pair of folding rolls therefor, of pivoted brackets on which said rolls are journalled, the pivots of the

brackets for each roll being located on the side of the other roll opposite the cylinder, means for applying spring pressure to hold the rolls in contact with each other, and means 5 for adjusting the spring pressure.

6. In a folding machine, the combination with a pair of folding rolls for receiving the folded product, of pivoted brackets on which said rolls are journaled, the pivots of the 10 brackets for each roll being so located that said brackets can swing on their pivots to bring their respective rolls away from the cylinder, an adjustable support for said pivoted brackets, and means for adjusting said 15 support circumferentially with respect to said folding cylinder.

7. In a folding machine, the combination with a pair of folding rolls, of a pair of pivoted brackets on which one of the rolls is 20 supported, the pivots of said brackets being located in a position beyond the roll and offset therefrom, whereby when the brackets swing away from the cylinder the roll will be moved directly away from its circumference, yielding means for holding said roll toward the cylinder comprising a spring at each end of it, a longitudinal shaft having a worm fixed on one end and provided with a collar loose on the other end having a worm thereon, 25 means connected with each of said worms for adjusting the resiliency of the spring at the respective ends of the shaft, and two adjacent wheels, one on the shaft and one on the collar located adjacent to each other for adjusting 30 the two worms either simultaneously or separately.

8. In a folding machine, the combination with a folding cylinder and a pair of folding rolls, of means for pivotally supporting one 40 of said rolls so that it can move directly away from the cylinder in case it encounters resistance, said means comprising a pair of brackets, a pin on the frame of the machine adapted to enter a depression in one of said brackets to normally hold the bracket against motion away from the cylinder, said pin being 45 adapted to be broken by the application of excessive strain to it, whereby the roll will be freed immediately and any paper choked 50 against the surfaces of the roll can be removed.

9. In a folding machine, the combination with a folding cylinder and a pair of folding rolls, of means for pivotally supporting one 55 of said rolls so that it can move, said means comprising a pair of brackets, a pin adapted to enter a depression in one of said

brackets to normally hold the bracket, said pin being adapted to be broken by the application of excessive strain to it, whereby the 60 roll will be freed immediately and any paper choked against the surfaces of the roll can be removed.

10. In a folding machine, the combination with a pair of folding rolls, of a pair of pivoted brackets on which one of the rolls is supported, yielding means for holding said roll in position comprising a spring at each end of it, a longitudinal shaft having a worm fixed on one end and provided with a collar loose on the other end having a worm thereon, 70 means connected with each end of said worm for adjusting the resiliency of the spring at the respective ends of the shaft, and two hand wheels rotatable on the same axis, one on the shaft and one on the collar located adjacent to each other for adjusting the two worms either simultaneously or separately.

11. In a folder, the combination with a folding roll, a screw adjustment for each end thereof, a worm for turning each screw, a shaft to which one worm is fixed, a collar rotatable on said shaft to which the other worm is fixed, and two hand wheels on the shaft and collar respectively for turning them individually to adjust either end of the folding roll, said hand wheels being located adjacent to each other so that they both can be turned with the same hand to adjust the roll bodily back and forth in a direction transverse to its 90 axis.

12. In a folder, the combination with a pair of folding rolls and means for adjusting each end of one of said rolls independently toward or from the other roll, said means 95 comprising two hand wheels independently rotatable on the same axis and located close together so that they can be turned at once to adjust both ends alike or either of them can be turned separately.

13. In a folder, the combination with a folding cylinder and a pair of folding rolls, of means for supporting said rolls, said supporting means having elongated curved slots at each end concentric with the folding cylinder and means for adjusting said rolls circumferentially with respect to the folding cylinders, an arm projecting from said supporting means for cooperating with the last named means, and means for holding the 100 rolls in any adjusted position along said slots.

In testimony whereof I have hereunto affixed my signature.

HENRY A. WISE WOOD.
